UNITED STATES PATENT OFFICE

HARVEY HUBBELL, OF BRIDGEPORT, CONNECTICUT; LOUIE E. HUBBELL EXECUTRIX
OF SAID HARVEY HUBBELL, DECEASED

ATTACHMENT-PLUG CAP

Application filed February 8, 1927. Serial No. 166,667.

This invention relates to attachment plug caps such as are used for connecting portable electrical devices to a suitable source of current supply through a suitable electrical receptacle, and relates especially to the construction of the contact blades carried by the cap to make the electrical contact with the stationary contacts in the receptacle, and has for an object to provide a contact blade which is much more rigid than the contact blades now generally employed, and therefore, cannot be easily broken or bent out of position in use.

It is also an object of the invention to provide contact blades in which the contacting surface between the blades and the contacts of the receptacle is greatly increased over the blades now generally employed, and thus gives a greater, better and more reliable electrical contact between them.

With the foregoing and other objects in view, I have devised the construction illustrated in the accompanying drawing forming a part of this specification. In this drawing,

Fig. 1 is a side elevation of an electrical receptacle showing my improved cap applied thereto, a portion of the body of the receptacle being broken away to show the engagement of the cap blade with a contact in the

socket.

Fig. 2 is a plan view of the lower end of the receptacle.

Fig. 3 is a plan view of the inner end of the cap.

Fig. 4 is a side elevation of the cap with a portion of the body broken away and also a portion of one of the blades broken away to more clearly show the construction.

Fig. 5 is a transverse section of one of the contact blades removed from the cap body, the section being substantially on line 5-5 of Fig. 6.

Fig. 6 is a side elevation of the blade shown in Fig. 5.

Fig. 7 is a side elevation of the blade looking from the right of Fig. 6.

Figs. 8 and 9 are side and edge elevations respectively of one of the members used to form the blade, and

Fig. 10 is a top plan view of the other member used to form the blade.

In the drawing I have shown a depending type of receptacle which may be attached to flexible leads, not shown, connected to any suitable source of current supply, but this receptacle is merely shown for illustration as the same type of receptacle is used for permanent wall or floor receptacles to cooperate with the attachment plug cap in exactly the same manner. The receptacle, as shown, comprises the usual insulating body member 10 having chambers or recesses therein carrying stationary contacts 11 electrically connected to the leads, not shown, and the receptacle body 10 has T-shaped openings or slots 12 leading to the recesses for passage of the contact blades of the caps to engage the stationary contacts in the usual manner. This socket is a standard type of socket which is adapted to receive the blades of both types of attachment plug caps now generally used, that is, where the blades are parallel or where they are arranged in alignment, and it will be noted that the contacts 11 have three spring side members 13 so as to engage the sides of the blades of either type of cap.

My improved construction comprises contact blades 14 which are substantially T-shape in cross section, and are mounted in an insulating body member 15 to project from one side thereof in the usual manner, as indicated in Fig. 4. Each blade comprises a leg portion 16 and a cross bar portion 17 arranged with the inner edge of the leg portion against the outer surface of the cross bar portion. Therefore, the cross bar portions 17 are opposed to each other and arranged in substantially parallel relation while the leg portions 16 extend outwardly from the cross bar portion and are substantially in the same plane, or in alignment. These blades may be integral with or may be rigidly attached to a base or plate 18 at their inner ends, which may be mounted in suitable recesses 19 in the body 15 and carry the usual binding screws 20 or any other means for attaching the lead wires to these plates and form electrical connection between these wires and the contact blades. In the present showing they are

mounted by means of screws 21 molded in the body extending through openings 22 in the plate and clamped in position by nuts 23, and the body 15 is provided with the usual opening 24 for passage of the lead wires, not shown.

The blades 14 may be made in one piece of extruded or drawn metal and T-shaped in cross section, but it is preferred to make them of two pieces as they are somewhat easier to make and have a somewhat more rigid connection with the mounting plate 18, but when the two sections are assembled they are in effect one piece. In the construction illustrated the plate 18 and the cross bar portions 17 are stamped in one piece, as shown, partly in full lines and partly in dotted lines, Fig. 10, and then the cross bar portion is bent up at right angles to the plate, as indicated in full lines, Fig. 10, and as also shown in Figs. 6 and 7. The plate 18 is provided on its opposite edge from the portion 17 with a notch 25. The leg portion 16 of the blade comprises a separate member, as shown in Figs. 8 and 9, which has adjacent its lower end a notch 26 leading from one edge thereof, and it also has on the same edge an extending lug or rivet 27 which when assembled projects into an opening in the cross bar portion 17 to secure the two elements together. In assembling, the member 16 is inserted in the notch 25 in the plate 18 and the portion of this plate 18 at the inner end of the notch 25 is seated in the notch 26 in the member 16. Thus the free edge 28 of the member 16 rests against the outer surface of the cross bar portion 17 and the end of the lug 27 is riveted over in the opening in the member 17 to secure the two members together. The edge of the member 16 may also be soldered to the surface of the member 17 if desired, but in either case it produces a substantially unitary construction. It will be apparent that this construction also provides an underhanging hook portion 29 engaging the under side of the plate 18 which gives a very rigid connection between the portions 16 and the plate, and as the cross bar 17 is integral with the plate it will be obvious that the T-shaped blade has a very rigid connection with the plate which will offer great resistance to bending in all directions. It will also be obvious that this construction of blade itself will be very rigid and have great strength and will offer great resistance to bending in all directions. This blade is, therefore, particularly adapted for use with heavy duty attachments such as are used in garages or factories where the ordinary type of blade may be easily bent out of position or broken and when bent is difficult to use because the blades are not in proper position to be inserted in the slots in the receptacle. With this construction it is very difficult to bend the blades out of position and the cap is, therefore, adapted for rough handling.

This cap, however, is not limited to heavy duty work as it is equally adapted for use for lighter attachments in the home. It will be apparent that these T-shaped blades may be readily inserted in the standard T-slots of the receptacle illustrated in Fig. 2, and another especially advantageous feature of these blades is that they each engage the three spring contact portions 13 of the stationary contacts in the receptacle and they, therefore, provide a much greater and much more reliable electrical connection with the contacts of the receptacle than do the blades now ordinarily used. Still further, these blades may be provided with recesses or openings 30 adapted to coat with the struckup lugs or bosses 31 on the receptacle contacts to resist withdrawal of the blades from the receptacle. Thus these blades are not as easily withdrawn from the receptacle and, therefore, there is much less liability of their being accidentally disconnected from the receptacle while in use.

Having thus set forth the nature of my invention, what I claim is:

1. An attachment plug cap comprising an insulating body member and a pair of contact blades each composed of two members, one of said members having a base to rest against the body and a laterally extending portion forming a portion of a contact blade, means for securing the base to the body, and a second member extending longitudinally of said blade portion at one side thereof and at substantially right angles therewith and forming with the blade portion a substantially T-shaped blade, means for rigidly securing one edge of the second member to the first member, and means for rigidly securing the inner end of the second member to the base. 90

2. An attachment plug cap comprising an insulating body member and a pair of contact blades projecting from one side thereof, at least one of said blades comprising two members one of said members having a base to rest against the body and a laterally extending portion forming a portion of a contact blade, means for securing the base to the body, and a second member extending longitudinally of said blade portion at one side thereof and at substantially right angles therewith and forming with the blade portion a substantially T-shaped blade, means for rigidly securing one edge of the second member to the first member, and means for rigidly securing the inner end of the second member to the base. 100

3. As a new article of manufacture a contact blade for attachment plug caps comprising two members, one of said members having a base adapted to be secured to a cap body and a laterally extending portion, a second member extending longitudinally of said portion at one side thereof and at substan- 125

tially right angles thereto to form with said portion a substantially T-shaped blade, cooperating means on said portion and one edge of the second member to rigidly secure said edge to said portion, and cooperating means on the base and one end of said second member to rigidly secure said end to the base.

4. As a new article of manufacture a contact blade for attachment plug caps, comprising a plate adapted to be secured to a cap body, an extension on one edge of said plate extending at substantially right angles to the plane of the plate, and a separate member secured to the plate at one end and extending longitudinally of and attached on one edge to said extension at one side thereof and with said extension forming a contact blade substantially T-shaped in cross section.

5. As a new article of manufacture a contact blade for attachment plug caps, comprising a plate adapted to be secured to a cap body, an extension on one edge of said plate extending at substantially right angles to the plane of the plate, said plate being provided in its opposite edge with a notch extending toward said extension, said extension providing the cross bar of a T-shaped blade, and a member extending longitudinally of said cross bar at one side thereof and at substantially right angles thereto to form the leg portion of the T-shaped blade, said member being seated in said notch and itself provided with a similar notch to receive said plate and provide an extension under the plate to secure said member to the plate.

6. As a new article of manufacture, a contact blade for attachment plug caps comprising a plate adapted to be secured to a cap body and including an integral extension at one edge extending at substantially right angles to the plane of the plate, and a separate member secured at one end to said plate and extending longitudinally of said extension at one side thereof and substantially at right angles thereto to provide a T-shaped blade, and means for securing one edge of said member to the extension to provide a substantially integral structure.

In testimony whereof I affix my signature.
50 HARVEY HUBBELL.
